US00D882959S

(12) **United States Design Patent** (10) Patent No.: **US D882,959 S**
 (45) Date of Patent: ** May 5, 2020

(54) **ORAL CARE IMPLEMENT**

(71) Applicant: **Colgate-Palmolive Company**, New York, NY (US)

(72) Inventors: **Wen Jin Xi**, Shanghai (CN); **Bo Zhang**, Yangzhou (CN); **Yanmei Ji**, YangZhou (CN); **Xiangji Ding**, YangZhou (CN); **Jianrong Zhou**, Yangzhou (CN)

(73) Assignee: **Colgate-Palmolive Company**, New York, NY (US)

(**) Term: **15 Years**

(21) Appl. No.: **29/673,402**

(22) Filed: **Dec. 14, 2018**

Related U.S. Application Data

(63) Continuation of application No. 29/586,988, filed on Dec. 8, 2016, now Pat. No. Des. 840,692, which is a continuation of application No. 29/533,942, filed on Jul. 23, 2015, now Pat. No. Des. 776,937.

(51) **LOC (12) Cl.** **04-02**

Primary Examiner — Steven J Czyz

CLAIM

The ornamental design for an oral care implement, as shown and described.

DESCRIPTION

FIG. 1 is a front perspective view of an oral care implement; FIG. 2 is a rear perspective view thereof; FIG. 3 is a front view thereof; FIG. 4 is a rear view thereof; FIG. 5 is a left side view thereof; FIG. 6 is a right side view thereof; FIG. 7 is a top view thereof; and, FIG. 8 is a bottom view thereof.

The broken lines depict portions of the oral care implement that form no part of the claimed design.

1 Claim, 4 Drawing Sheets
